UNITED STATES PATENT OFFICE.

OLIVER J. BATES, OF TILTON, IOWA.

IGNITER-GEAR FOR EXPLOSIVE-ENGINES.

946,816.

Specification of Letters Patent. Patented Jan. 18, 1910.

Application filed May 20, 1908. Serial No. 433,994.

To all whom it may concern:

Be it known that I, OLIVER J. BATES, a citizen of the United States, residing at Tilton, in the county of Poweshiek, State of Iowa, have invented certain new and useful Improvements in Igniter-Gears for Explosive-Engines; and I do hereby declare the following to be a full, clear, and exact description of the invention, such as will enable others skilled in the art to which it appertains to make and use the same.

This invention relates to igniter gear for explosive engines.

In certain types of explosive engines, wherein a governor is provided for opening the exhaust and keeping it open when the engine is running above a certain speed, no means is provided for eliminating the spark during the time the exhaust is being held open and it is therefore the object of my invention to provide such means.

The invention is embodied in a simple mechanism which is arranged in operative relation to the igniter trip rod of the engine and is operated by the valve rod, when the said rod is moved to position to hold the exhaust open under conditions mentioned above, to lift the igniter trip rod and thereby eliminate the spark which would otherwise result.

In the accompanying drawings, Figure 1 is a side elevation of an explosive engine of the ordinary type showing the application of my invention thereto, Fig. 2 is a top plan view thereof, Fig. 3 is a detail side elevation of a portion of the engine and of the mechanism embodying my invention the several elements of the said mechanism being shown in normal position, Fig. 4 is a similar view but showing the position assumed by the several elements of the mechanism when the speed of the engine has reached an abnormal degree, and, Fig. 5 is a detail perspective view of the mechanism removed from the engine.

As the engine itself forms no part of my invention, a brief description of it will suffice.

As shown in the drawings, the engine cylinder is indicated by the numeral 10, the movable igniter electrode by the numeral 11,

the valve rod by the numeral 12, and the igniter trip rod by 13. As is usual, the valve rod is operatively connected with the rocker 14 which is oscillated by the rotation 55 of the cam 15 carried by the shaft 16 which is in turn driven from the engine shaft which is indicated by the numeral 17. The igniter trip rod is oscillated by reason of an eccentric connection 18 had with the shaft 60 16 and rests adjacent its free end upon the usual roller 19 which is mounted to rotate upon the ordinary stud bolt 20 upon the side of the engine cylinder, it being understood that when the engine is in operation, 65 the outer or free end of the said rod 13 describes substantially a circle and that at each cycle, it trips the igniter electrode 11. It is with the engine mechanism so far described that the controlling mechanism embodying 70 my invention is associated and the said controlling mechanism will now be specifically described.

A triangular rocker 21 is mounted for oscillatory movement upon the stud bolt 20 75 and lies outwardly of the igniter trip rod and journaled upon this rocker adjacent one corner thereof is a small roller 22 which at all times lies beneath the igniter trip rod. The lower end of the rocker extends to one 80 side of the valve rod of the engine and upon the said valve rod is fixed a stud or pin 23 which is designed to engage with the edge of the rocker 21 and oscillate the same under conditions which will now be explained. 85

As is usual in an engine of this general type, when the speed thereof reaches an abnormal degree, the valve rod 12 is shifted to position to open the exhaust by mechanism actuated by a governor, the latter being shown at 24, and is locked in this position until the speed of the engine has decreased and when the valve rod is so shifted, the rocker 21 is oscillated or rocked to the position illustrated in Fig. 4 of the drawings 95 thereby bringing the roller 22 into engagement beneath the igniter trip rod and raising the same so that its free end will not engage with the igniter electrode 11. It will be understood, of course that sparking is in 100 this manner eliminated until the speed of the engine assumes a normal degree.

What is claimed is:

In an igniter gear for internal combustion engines, the combination with an igniter trip rod, and a governor controlled valve rod; of a rocker having means engageable with the trip rod to move the same out of the path of the electrode, and a pin on the valve rod for actuating the rocker, said valve rod, rocker and pin being mounted

and arranged to move the trip rod out of the 10 path of the electrode while the valve rod is in position to hold open an exhaust valve.

In testimony whereof, I affix my signature, in presence of two witnesses.

OLIVER J. BATES.
